Fig. 6

Fig. 7

Fig. 8

FIG. 1 is a front elevation of a sterilizer cabinet showing my new design, with the cover member in an open position;

FIG. 2 is a right side elevation thereof;

FIG. 3 is a rear elevation thereof;

FIG. 4 is a top plan view thereof;

FIG. 5 is an isometric view thereof;

FIG. 6 is an isometric view similar to FIG. 5 with the cover member in a closed position;

FIG. 7 is a side elevation thereof taken from the left of FIG. 8;

FIG. 8 is a front elevation thereof.

The electric cord element has been omitted in FIGS. 1 and 3 for convenience of illustration.

I claim:

The ornamental design for a sterilizer cabinet or similar article, as shown and described.
